NORMAN KAY, OF JOBOS, PORTO RICO

CANE MILLING APPARATUS

Application filed September 29, 1927. Serial No. 222,896.

My invention relates to cane milling apparatus, and more particularly to a rotary cane knife designed for use in a cane mill for preparing the cane for subsequent crushing and juice expressing operations.

A cane mill generally includes one or more preliminary crushers in the form of cooperating pairs of rotary toothed rolls, which crush and disintegrate the cane, which then passes through a tandem of three-roll mills, between the rolls of which the cane is heavily pressed to extract the juice. The cane acted on by the preliminary crusher is generally in the form of a relatively deep tangled blanket of cane stalks, and considerable power is required to drive the crusher in handling this blanket.

In order to reduce the amount of power necessary to drive the preliminary crusher, and to bring about a thorough disintegration of the cane at an early stage in its passage through the mill, so that the subsequent juice expressing operations may be efficiently carried out, it has been proposed to use a series of rotatable knives, for cutting up the cane

before it reaches the preliminary crusher in order that the cane acted on by the latter may be reduced to a somewhat shredded condition, whereupon it will feed through the crusher more readily and permit the crusher to more thoroughly separate the fibers of the cane. The cane is usually carried to the mill by means of an endless belt, and rotary knives have been mounted above such belt, so as to engage the cane as it passes to the mill. The

knife contemplated in the present invention is in general of the above mentioned type, and may be used, if desired, to act on cane while supported on a conveyer and passing to a preliminary crusher, and the invention has for its primary object a knife capable of operating on the cane more efficiently than those previously known.

The knives used heretofore have been provided with smooth cutting edges which are intended to slice into the cane and cut it into fragments. This arrangement of knives is effective to a degree in bringing about a condition of the cane blanket where it may be more efficiently acted on by the crusher rolls, but it has not produced the expected results

as regards the improvement of the milling. Knives of the kind ordinarily used are apt to strike the cane stalks with glancing blows, the effect of which upon the cane body as a whole is negligible. My present invention 55 contemplates the production of a power driven cane knife which preliminarily shreds the incoming mass of cane to a very considerable degree, and thereby materially reduces the amount of work to be done by the rolls following the knives, so that in many cases 60 the number of rolls in a given cane mill can be reduced to advantage if my cane knife is used for preliminary treatment of the cane.

In a more specific aspect, it is a further object of the invention to provide a knife of the above type, having a cutting edge provided with a series of serrations or notches adapted to hook into the cane and shred it, in addition to the ordinary cutting and chopping action.

To these and other ends, the invention consists in the novel features and combination of parts to be hereinafter described and claimed.

In the drawings:

Fig. 1 is a fragmentary view, partly in section, of a cane mill, showing an arrangement of knives, according to my invention, associated therewith;

Fig. 2 is a somewhat diagrammatic plan 80 view of the conveyer shown in Fig. 1, and the arrangement of knives associated therewith;

Fig. 3 is a view of a knife, according to my invention, on an enlarged scale;

Fig. 4 is a fragmentary view of the cutting edge of the knife shown in Fig. 3.

Fig. 5 is a fragmentary view of a modification; and

Fig. 6 is a fragmentary view of the cutting edge of a knife shown in Fig. 5.

Referring to the drawings in which I have shown a preferred embodiment of my invention, the reference numeral 5 indicates, in general, a portion of a cane mill, including as a part thereof a conveyer 6, provided with an endless belt 7, having secured on the outer surface thereof a series of slats 8, adapted to conduct cane to a preliminary crusher 9, which may be of any well-known or preferred type. The conveyer 6 is provided with side 95

walls 10, adapted to prevent the escape of cane from the mill, and above the side walls 10 is a rotary shaft 11, mounted in bearings 12 and 13, supported in any suitable manner on the mill 5, or on any convenient or adjacent support.

Secured on shaft 11 and between the side walls 10 of the conveyor 6 is a series of spiders 14, provided with arms 15, each arm having secured thereon, by suitable means, a cane knife 16. Each of the cane knives 16 comprises a shank 17, tangentially arranged on an arm 15, and a blade 18, curved or bent back from the direction of movement of the knife, and provided with a cutting edge 19, which is interrupted by notches or serrations 20, each notch or serration having a cane engaging face 21, substantially at right angles or normal to the cutting edge of the blade, and another face 22 extending towards the shank and intersecting the cutting edge of the blade at an acute angle. The edges of the faces 21 are beveled as at 21^a to provide relatively sharp cutting edges. The rotary shaft 11 may be driven in any suitable manner, and above the conveyor 6 and partially surrounding the rotary knives 16 is a shield 23 adapted to prevent any pieces of cane from being thrown out of the mill by the rotating knives.

In the form shown in Figs. 5 and 6, the notches 20^b are in general of the same shape and disposition as the notches 20 previously described, having abrupt shoulders 21^b and gradually sloping surfaces 22^b, but the shoulders 21^b in this case are not beveled or chamfered. In both cases, however, the abrupt shoulder is directed away from the free end of the knife and faces toward the axis of rotation and presents a cane penetrating edge of some width, disposed generally transversely to the knife and to the line of travel of the cane body. As shown in the drawings, the active or leading marginal edge portion of the knife blade is beveled or cut away at opposite sides so as to be reduced in thickness toward the extreme edge. The leading edge toward the heel is shaped to cut in a lengthwise direction only but the leading edge of the curved outer end portion is cut away (as shown in Fig. 4 or in Fig. 6) to present a plurality of the transverse projections alternating with which are short longitudinally cutting portions formed by leaving the beveled edge uncut at those points.

In operation, sugar cane is carried by the conveyor belt 7, and the slats 8 thereon, to the preliminary crusher 9, passing under the rotary knives 16, which extend into the conveyor to a point closely adjacent the slats 8 of the belt 7, and are rotated at a relatively high speed. The cutting edges 19 of the blade 16 engage the cane to cut it up into pieces, the teeth formed by the notches 20 of the blades hooking into the cane and tearing it and shredding it, in addition to the normal cut-

ting and chopping action of the blade. The notches or serrations are so formed as to provide on each revolving blade or arm a plurality of claws, spaced apart longitudinally of the arm, which repeatedly engage and tear apart the stalk portions supported on the comparatively slowly moving conveyor and progressively presented for the action of said arms, so as to separate the fibers and disintegrate the cane. The shredded cane is carried by the belt 7 to the preliminary crusher 9, where it is acted on in a well-known manner.

The blanket of cane carried by the conveyor belt 7 to the preliminary crusher is of considerable depth and the rotating knives 16 are so arranged in the conveyor 7 as to cut into the blanket of the cane to quite a depth, in order that substantially all of the blanket may be acted on and shredded by the knives. In practice, it has been found that it is desirable to separate the knives 16 from the slats 8 about 3½ inches, although this distance may be varied to suit conditions.

By shredding the cane previous to its being acted on by the preliminary crusher, the amount of power necessary to drive the crusher is reduced, and the cane more thoroughly disintegrated at an early stage in its passage through the mill, whereby the juice expressing operations may be more efficiently carried out.

In practice, my improved cane knife has shredded to a quite complete and satisfactory degree the entire body or mass of cane moving toward the mill on the conveyer. This I ascribe to the serration of the knife blades, and more particularly to the fact that the blades are provided with a plurality of transverse cane shredding edges located at the edge of the blade in planes which are approximately normal to the plane of the blade itself. These shredding edges grip, bite into and tear apart the cane stalks, which lie upon the conveyer in a dense mass so as to offer effective resistance and prevent displacement of the stalks away from the rearwardly bent or curved tips of the blades. This shredding action is in addition to the cutting or chopping action produced by the cutting edge with which the notches or serrations are associated, but this ordinary cutting edge running lengthwise of the blade is not essential in all aspects of the invention. Owing to the location of the knife so that the blade tips extend into close proximity to the conveyer, and so that the blades penetrate substantially to the lowermost layer of cane on the conveyer, the entire mass of cane on the conveyer is subjected to the shredding action and quite uniformly shredded. As a result, it has been possible to feed the cane into the mill in a considerably disintegrated condition, thus decreasing the amount of work to be done by the mill rolls, and mate-

rially increasing the thoroughness of the juice extraction.

While I have shown a preferred embodiment of my invention, it will be understood that the same is not to be limited to all the details shown, but is capable of modification and variation within the spirit of the invention and the scope of the appended claims.

What I claim is:

1. In a cane mill, means for feeding cane, and means for engaging and shredding the cane while being fed, said last named means comprising a rotary shaft, a series of cutting knife blades carried on said shaft and extending outwardly therefrom, and clawlike means formed on said blades adapted to hook into and shred cane.

2. In a cane mill, means for feeding cane, and means for engaging and shredding the cane, while being fed, said last named means comprising a rotary shaft, a series of knives mounted on said shaft, and extending outwardly therefrom, and notched cutting edges on the forward or leading edges of said knives, each of said edges being constructed to penetrate the cane along lines generally transverse to its direction of travel.

3. In a cane mill, means for feeding cane, and means for engaging and shredding the cane while being fed, said last named means comprising a series of circumferentially spaced rotatable arms and a plurality of clawlike teeth on the forward or leading edge of each of said arms to hook into and shred the cane.

4. In a cane mill, means for feeding cane, and means for engaging and shredding the cane while being fed, said last named means comprising a rotary shaft, a series of arms on said shaft extending outwardly thereupon, the outer ends of said arms being curved back from the direction of movement of said arms, and a plurality of teeth on the curved outer ends of each of said arms presenting shoulders substantially normal to the leading surface of the arm.

5. In a cane mill, means for feeding cane, and means for engaging and shredding the cane while being fed, said last named means comprising a rotary shaft, a series of knives mounted on said shaft, and cutting edges on said knives, there being angular notches in said cutting edges, each of said notches having one side thereof substantially normal to the adjacent edge of said knife.

6. In a cane mill, means for feeding cane, and means for engaging and shredding the cane while being fed, said last named means comprising a rotary shaft, and a series of knives extending outwardly therefrom, said knives being provided with cutting edges, the outer ends of said cutting edges being curved back from the direction of movement of said knives, there being a series of abrupt trans-

verse shredding shoulders along the curved portions of said cutting edges.

7. A shredding device for cane mills, comprising a rotary shaft having circumferentially spaced arms with rearwardly curved ends, and shredding teeth associated with said ends presenting shoulders substantially normal to the leading surfaces of the arms.

8. A cane disintegrating device comprising a plurality of revolving arms having generally transverse projections presenting clawlike portions on their leading surfaces to tear apart the cane stalks.

9. A cane disintegrating device comprising a plurality of arms revolvable as a unit and having clawlike portions facing toward the axis of revolution.

10. A cane disintegrating device comprising a plurality of outwardly extending flat arms having a common axis of rotation and presenting clawlike edge portions to the cane.

11. A device such as described, comprising a shaft, arms secured to and extending outwardly therefrom and having free outer ends, and abrupt cane shredding shoulders on the arms facing away from said free ends.

12. A device such as described, comprising a rotary shaft, an arm extending outwardly therefrom, and abrupt cane shredding shoulders of some width extending transversely of the arm and facing away from the free end thereof.

13. A rotary cane disintegrating unit having an outwardly extending arm with a free backwardly turned outer end portion, and a plurality of clawlike projections associated with the leading edge of said backwardly turned portion.

14. A rotary cane disintegrating unit having arms with free backwardly turned outer end portions notched on their leading edges to present a series of spaced cane tearing shoulders facing away from the free ends of the arms.

15. A rotary cane disintegrating unit having arms with free backwardly turned outer end portions notched on their leading edges to present a series of spaced cane tearing shoulders facing away from the free ends of the arms, said shoulders extending generally transversely of the arm and being of appreciable width.

16. The combination with a travelling conveyor for feeding a body of cane, of a device adjacent the path of travel of said conveyor for disintegrating the passing cane on the conveyor, said device comprising a series of rotary arm members each having longitudinally spaced shoulders substantially facing the axis of rotation and presenting a plurality of cane penetrating teeth.

17. The combination with a cane shredding device comprising power driven members each having a series of clawlike cane

engaging and shredding projections, of a travelling conveyor for feeding cane on which the cane is supported and shredded by said projections while in transit.

5 18. The combination with a travelling cane conveying belt, of a power driven cane disintegrating device in a fixed position relatively to the belt for action on the passing cane on the upper belt face and having a 10 series of angularly notched clawlike cane shredding edge portions arranged to be presented toward the belt and to move into and through a portion of the cane body supported on the belt.

15 19. A revolving cane knife having a cane cutting edge portion presented in the direction of cane travel and a transverse shredding edge portion.

20 20. A revolving cane knife having a marginal portion reduced in thickness toward the extreme edge and provided with a plurality of transverse shoulders facing away from the free end.

25 21. A revolving cane knife having a marginal portion reduced in thickness toward the extreme edge, parts of said marginal portion presenting cutting edges disposed in the direction of cane travel, and other parts presenting a plurality of transverse 30 cane shredding shoulders.

22. A revolving cane knife having a marginal portion presenting a plurality of longitudinal cutting edges and a plurality of transverse cane shredding shoulders.

35 23. A revolving cane knife bent back at the outer end, the leading edge toward the heel being shaped to cut in a lengthwise direction only but the leading edge of the outer end portion presenting a plurality of clawlike projections.

40 24. A cane knife having its blade edge provided with a series of transverse cutting portions and a series of longitudinal cutting portions.

45 25. A cane knife having its blade edge provided with a series of transverse cutting portions and a series of longitudinal cutting portions, said portions alternating.

50 26. A cane knife blade having wide transverse shredding portions spaced along its edge and facing away from the blade tip.

55 27. The combination with a rotary cane disintegrating unit having a multiplicity of abrupt transverse shoulders at the periphery 60 presenting clawlike elements for tearing apart the cane, of a travelling conveyor for feeding cane to and past said unit, a substantially flat surface of said conveyor supporting the cane while acted upon by said clawlike elements.

In witness whereof, I have hereunto set my hand this 13th day of September, 1927.

NORMAN KAY.
